UNITED STATES PATENT OFFICE.

JOSEPH G. GROFF, OF BUFFALO, NEW YORK.

HOLDER FOR PAPER BAGS AND SIMILAR ARTICLES.

1,340,335.

Specification of Letters Patent. Patented May 18, 1920.

Application filed February 10, 1920. Serial No. 357,553.

To all whom it may concern:

Be it known that I, JOSEPH G. GROFF, a citizen of the United States, residing at Buffalo, in the county of Erie and State of New York, have invented certain new and useful Improvements in Holders for Paper Bags and Similar Articles, of which the following is a specification.

My invention relates to improvements in holders for paper bags and similar articles, and it has for its primary object the provision of a holder of this type whereby paper bags can be suspended in a uniform manner and so that they can be conveniently removed from the holder separately or in any quantity needed.

Other objects are to provide a holder of this type whereby paper bags or like articles can be conveniently assembled and retained in assortments, either according to grades of material or sizes, and wherein provision is made to enable paper bags of a certain size or grade to be placed on the holder without disturbing the bags of other grades or sizes held thereby.

With these and other objects in view, the invention consists in the novel features of construction and in the arrangement and combination of parts to be hereinafter described and more particularly pointed out in the subjoined claims.

In the drawings:—

Figure 1 is a side elevation of a paper bag holder provided with holding devices for holding bags or other articles in convenient form according to the grade of material or the size of the bags or other articles suspended therefrom.

Fig. 2 is a detached perspective view of one end of the holder showing one complete holding device.

Fig. 3 is a longitudinal section through the holder along the length of one of the holding devices.

In preferred form I employ a tube 4 and preferably thread the ends thereof internally, as at 5. Inserted into said threaded ends are ornamental stud-caps 6, said caps having threaded portions 7 to engage the internal threads of the tube and any suitable form of ornamental head 8 to give the tube, or "main support" as it may be termed, a finished appearance. This tube or support may be secured in a suitable position in any approved manner, but I preferably attach to opposite ends thereof eye-bolts 9, the

threaded ends of which are threaded into the tube, as at 10. The eyes of these bolts are left open for conveniently attaching the tube or support to the lowermost links 60 of a pair of suspended chains 11 fastened to the ceiling or any elevated object.

While the eye-bolts and chains provide convenient and neat appearing means for suspending the tube or support and also 65 offer the advantage of easily detaching the holder from its suspending means, it is nevertheless apparent that within the wider scope of my invention, other suitable and convenient means may be employed to support the holder in position.

The tube or support is preferably formed of metal, and although I have shown a cylindrical tube, it may have any other cross sectional shape or may be formed 75 solid, or of any other material possessing the required rigidity for attachment thereto of the bag holding devices to be presently described and for supporting the weight of the paper bags or other articles fastened 80 to the holding devices.

Each of the holding devices proper comprises two vertical or depending members 12, 13 and a horizontal comparatively slender pointed member 14 pointed at one end, 85 as at 15, and threaded or otherwise fastened into the vertical or depending member 12, as at 16.

The tube or main support 4 is provided with diametrically opposite openings 17 at 90 one or more points along its length, these openings being arranged in pairs when the supporting member is in the form of a tube; but when a solid support is employed, it is apparent that a single opening only will be 95 required. In each pair of openings 17, a vertical or depending member 12 of the bag holder is slidably and rotatably arranged, and each of said slideable and rotatable members 12 is preferably reduced in diameter at its upper end and threaded for attachment thereto of a suitable nut 18 having a base of greater diameter than said member 12 so that it serves as a stop to limit the downward movement of said member. 100 The nuts 18 are preferably ornamental so as to give the device a neat appearance.

Each of the vertical members 12 is enlarged at its lower end, at which point the slender member 14 is threaded into it, and 110 each of the vertical members 13 has its upper end threaded into the tube or support 4

and has its lower end formed into a hook, as at 19, the bight of the hook serving as a support for the pointed end of said slender member. Each of the slender members 14 5 may be termed a penetrating element, and by reason of the vertical members 13 being fixedly retained on the tube or support 4 while the vertical members 12 are slidable, the penetrating elements secured to the 10 lower ends of the vertical members 12 may be elevated therewith so as to disengage the pointed ends of said penetrating elements from the hooks of the fixed vertical members 13.

15 When the penetrating element of a holding device is disengaged from its receiving hook, the slidable and rotatable member 12 may be rotated to swing the penetrating member into a position at an angle to the 20 tube or support, as clearly shown in dotted lines in Fig. 2, thus permitting paper bags to be conveniently fastened to the penetrating member either by forcing them over the pointed end of said member and along the 25 same or by providing the bags or other articles with suitable openings to permit the bags to be conveniently slipped onto the penetrating member.

When the desired number of assembled 30 bags or other articles are applied to the penetrating member, the penetrating member with the bags or other articles thereon may be swung laterally to a position underneath and in line with the tube or support, 35 which will be permitted by reason of the vertical member 12 being rotatably mounted in said tube or supporting member, after which said vertical member 12 and the penetrating member 14 with its bags may be 40 lowered to bring the pointed end of said penetrating member into engagement with the hook of the fixed vertical member 13. When the penetrating member is in this 45 position, it will prevent rotation of the vertical member 12.

While I have shown a series of holding 50 devices applied to the tube or support, it is quite clear that the length of the tube or support may be reduced to support only a single holding device.

Each of the holding devices may be said 55 to comprise a fixed member and a slidable and rotatable member having a bag supporting member attached thereto, and that under this principle the device may be modified in various ways without departing from the spirit of my invention or sacrificing any of the advantages thereof.

Having thus described my invention, what 60 I claim is:—

1. A bag holder, comprising a support, a member depending from and fixed to said support, a combined slidable and rotatable member retained on said support and arranged parallel with said fixed depending

member, and means on said combined slid- 70 able and rotatable member onto which paper bags are adapted to be secured, said means being held in engagement with said fixed de- pending member to prevent rotation of said combined slidable and rotatable member.

2. In a bag holder, two spaced parallel members, one of said members being slid- 75 ably and rotatably supported and having a bag retaining member adapted to engage the other member.

3. A bag holder, comprising two spaced parallel members, one of said members hav- 80 ing a fixed position and provided with a hook at one end and the other being slidably and rotatably mounted and having a slender penetrating member secured thereto, said penetrating member being adapted for engagement with the hook of said fixed member.

85 4. A paper bag holder, comprising a sup- port, a pair of spaced parallel members car- 90 ried by said support, one of said members being fixedly secured with one end to said support and having a hook at its other end, the other of said pair of members being slidably and rotatably mounted in said sup- port, and a slender bag-carrying member having one end secured to the lower end of 95 said slidable and rotatable member and its other end adapted to engage the hook of said fixedly-secured member.

5. A bag holder, comprising a support, a slidable and rotatable member mounted in said support, a fixed member parallel 100 with said slidable and rotatable member se- cured with one end to said support and hav- 105 ing a hook at its other end, and a bag pen- etrating member secured to said slidable and rotatable member and adapted to have its other end engaging the hook of said fixed member.

6. A bag holder, comprising an elongated support having a series of bag holding 110 devices suspended therefrom, each of said bag holding devices comprising two spaced de- pending members, one of said members be- 115 ing fixedly secured to said support and hav- ing a hook at its lower end and the other being slidably and rotatably mounted in said support and provided with a bag-carry- 120 ing member arranged at right angles thereto and adapted to engage the hook of said fix- edly-secured depending member.

7. A bag holder, comprising a tube, means 125 for supporting said tube, and a bag holding device depending from said tube and com- 130 prising two spaced depending members, one of said depending members having its up- per end threaded into said tube and being provided with a hook at its lower end and the other member being slidably and rotatably mounted in said tube and having a bag-retaining member at its lower end parallel with said tube and adapted for en-

gagement with the hook of said first-mentioned depending member.

8. A bag holder, comprising a tube having openings at diametrically opposite points, a member slidable and rotatable in said openings and having a reduced threaded portion at one end, a nut applied to said threaded portion and bearing against said tube to limit the movement of said member in one direction, a second member parallel with said first member and spaced therefrom, said second member being fixedly attached with one end to said tube, and a slender bag-retaining member secured to the lower end of said first-mentioned member and detachably connected to the lower end of said second member.
9. A bag holder, comprising a horizontal tube, two spaced members depending from said tube, one of said members being threaded with its upper end into said tube and having

a hook at its lower end and the other being slidably and rotatably mounted in said tube, means at the upper end of said slidably and rotatably mounted member to retain the same in said tube, and a bag-penetrating member threaded with one end into the lower end of said slidably and rotatably mounted member and having its other end pointed and engaged with the hook of said first-mentioned member.

10. A bag holder comprising two parts, each part having two fixedly connected members at right angles to each other, one part having one of its members slidable and rotatable in one of the members of the other part and its other member adapted for detachable engagement with the other member of said other part.

In testimony whereof I affix my signature. 40

JOSEPH G. GROFF.
